ABSTRACT: A press control system which includes a clutch mechanism and a pneumatic circuit for actuating the clutch mechanism, including a clutch valve. An electrical run circuit actuates the clutch valve, the circuit comprising dual run-jog buttons which must both be depressed for energizing the circuit. The circuit also includes a holding switch which permits the flow of current to the clutch valve solenoid when the dual run-jog buttons are released, and an antirepeat relay which prevents repeat strokes in the event the run-jog buttons remain in the depressed position. The improvement of the present invention comprises an interlock arrangement between the pneumatic circuit and electrical run circuit including switch means actuated by said clutch valve to prevent the flow of current to said antirepeat relay means in the event of a malfunction on the part of components of the electrical or pneumatic circuit, or through said holding switch until the clutch valve opens.

PRESS CONTROL ELECTRICAL AND PNEUMATIC INTERLOCKING

The present invention pertains to the art of controls for machines, and more particularly to a novel control arrangement for presses of the reciprocating type.

The invention is particularly applicable to controls which utilize both an electrical control circuit and a pneumatic actuating circuit, and to a novel safety interlock arrangement between the two circuits by which one or both of the circuits are deenergized on failure of components therein. Although the invention will be described with reference to a press, it will be apparent that principles of the invention are applicable to other types of machinery.

The invention also is particularly applicable to single-stroke operation of a press or other type of machinery, although the principles of the invention are applicable to control circuits designed for continuous operation as well as single-stroke operation.

In a reciprocating press, there usually is provided a motor for driving the press, associated with a clutch mechanism which connects the motor to the press crankshaft, and a pneumatic system which actuates the clutch mechanism. The pneumatic system, in addition to an air supply utilizes an air valve which when opened allows the flow of air from the air supply to the clutch mechanism.

A conventional electrical control circuit for the above press uses a start button to energize the motor starter. In parallel with the motor solenoid is a clutch circuit containing the coil for the air valve solenoid. An important part of every clutch circuit are two button-actuated contacts which are series connected in the circuit requiring an operator to use both hands to energize the circuit. Frequently the clutch circuit will be divided into a run circuit and a jog circuit which are energized separately, in which case each circuit would use series connected contacts. Mechanical connections between the "run" contacts and the "jog" contacts permit the use of a single pair of buttons, with the result that these buttons are known as "run-jog buttons".

Although the "jog" portion of the clutch circuit usually is set simply by a jog selector switch (allowing the operator to jog or advance the press in steps by depressing both the run-jog buttons) the "run" portion of the circuit, for single-stroke operation, requires the use of a series of relays and switches which permit the clutch to be engaged only after a number of conditions have been met, and cause the clutch to be disengaged at a particular point in the press stroke.

A frequently used switch in the "run" portion of the clutch circuit is a holding switch which connects the clutch coil with the power supply after the press has been started. The purpose of the holding switch is to permit the operator to release the run-jog buttons once the press has started, without stopping the press, but the problem is that should this switch fail or relays in this portion of the circuit, the clutch coil could be energized without depressing the run-jog buttons.

Also, there is always the danger that the operator will hold the run-jog buttons in a depressed position for too long, causing the press to inadvertently repeat. To prevent this, it is conventional practice to provide in the clutch circuit an antirepeat relay which prevents the clutch coil from being energized, or reenergized without releasing the run-jog buttons and again depressing them.

Although the antirepeat relay provides a measure of safety, it is possible that even this relay can become stuck in an energized position in which case its antirepeat value would be lost.

Similarly, other relays or switches could fail, as could the clutch valve itself, or the coil actuating the valve.

It is known to provide an interlock between the clutch air valve and "run" portion of the press electrical circuit which utilizes limit switches actuated by the air valve poppets interlocked into the circuit. Still, the shortcoming of this method is that if the air valve were to fail in the open position, air would be fed directly to the press clutch, causing the clutch to engage, in turn, causing repeat strokes of the press slide.

It also is known to associate a pneumatic interlock with the clutch air valve, installed on the valve itself, but this interlock is so sensitive that it is not often used, and there is no means for monitoring the pneumatic interlock electrically.

Accordingly, it is an object of the present invention to overcome the above disadvantages, and in particular to provide a novel and improved interlocking arrangement which effectively prevents repeat strokes of a press slide or other machine in the event of a failure of components of either or both of the electrical and pneumatic circuits for the press.

In accordance with the present invention there is provided a press-control system which includes a clutch mechanism and a pneumatic circuit for actuating the clutch mechanism, including a clutch valve. An electrical run circuit actuates the clutch valve, the circuit comprising dual run-jog buttons which must both be depressed for energizing the circuit. The circuit also includes a holding switch which permits the flow of current to the clutch valve solenoid when the dual run-jog buttons are released, and an antirepeat relay which prevents repeat strokes in the event the run-jog buttons remain in the depressed position. The improvement of the present invention comprises an interlock arrangement between the pneumatic circuit and electrical run circuit including switch means actuated by said clutch valve to prevent the flow of current to said antirepeat relay means in the event of a malfunction on the part of components of the electrical or pneumatic circuit, or through said holding switch until the clutch valve opens.

Preferably, the interlock arrangement includes a line in parallel with the clutch solenoid containing an interlock relay and a normally open switch which is closed when said clutch valve is in the open position. A normally open contact in series with the holding switch responsive to the interlock relay prevents a flow of current through the holding switch until the clutch valve has been opened by depressing both the run-jog buttons.

Normally closed contacts in series with the relay for the press motor responsive to said interlock relay prevents the motor from being energized in the event the clutch valve is stuck in the open position.

In a preferred embodiment in accordance with the invention, a master solenoid valve is positioned in series with the clutch valve, the electrical circuit including clutch valve relay means through which the clutch valve and master solenoid valves coils are energized on depressing the dual run-jog buttons. Switch means are provided responsive to the position of the master solenoid valve operable to prevent the clutch valve relay means from being energized should the master solenoid valve be stuck in the open position.

It will become apparent from the above and other embodiments of the present invention, that there is provided a novel safety interlocking system, including an electrically interlocked series piping of air valves which insures that all valves, switches and relays must be operative before the press will run or repeat.

The invention and advantages thereof will become more apparent upon consideration of the following specification, with reference to the accompanying drawings, in which:

FIG. 1 is a schematic illustration showing the press pneumatic system in accordance with the invention;

FIG. 2 is an electrical diagram illustrating an electrical control circuit in accordance with the invention; and

FIG. 2A is a graph showing operation of switches of the control circuit of FIG. 2 in accordance with the invention.

Referring to the drawings, the press is provided with a crankshaft A (FIG. 1) which is driven by a motor B through a clutch C, the latter being pneumatically actuated by air from an air supply D through a master solenoid valve E and dual clutch air valve F, the components D, E and F constituting the pneumatic actuating circuit or portion of the press. An electrical circuit (FIG. 2) for the press comprises a three-phase supply circuit G which powers the motor B, and a control circuit H which is supplied with power from the three-phase circuit by means of a transformer I. The control circuit can

generally be considered as having a first motor start circuit J, and a clutch circuit K, the latter including a "run" portion L and "jog" portion M.

Returning to FIG. 1, the press crankshaft A is actuated by the motor B through the clutch C, engagement of the clutch causing the crankshaft to turn with the motor and raise and lower a press slide. To engage the clutch, both the master solenoid valve E and dual clutch air valve F must be in the open position, since these valves are in series with each other and between the source of air and the clutch.

The dual clutch air valve F is a known valve which comprises identical series connected valve mechanisms in a single valve housing. The reason for its use in this instance is one of safety since it is essential that the press clutch be engaged only after a series of conditions have been met. If one of the valve mechanisms fails in the open position, the other valve mechanism is still closed to prevent air from reaching the clutch housing throwing the clutch into engagement.

As will be shown the master solenoid valve E provides a means for interlocking the press electrical control circuit with the pneumatic circuit for further safety to prevent inadvertent engagement of the clutch.

Actuation of the dual clutch air valve is by means of solenoids 20 and 22 connected to spools for the valves; a third solenoid 24 actuating the spool for the master solenoid valve E for opening and closing this valve.

Also illustrated in FIG. 1 is a pressure switch PS-2 connected with the outlet port for the master solenoid valve E; and four limit switches, RLS-1, RLS-2, RLS-3 and RLS-4, actuated by cam means 26 mounted on the crankshaft. The functioning of the pressure switch, cam and limit switches will be described.

Further, as shown in FIG. 1 the poppets for the dual clutch air valve F are arranged to open and close limit switches LS-A and LS-B, the functioning of these switches to be described.

Turning now to FIG. 2, the three-phase circuit G, which supplies current to the motor B is conventional simply containing normally open contacts M-1, M-2, M-3 which must be closed before current can be supplied to the motor.

To close the contacts, the motor-start circuit J (which includes lines 3, 4 and 5 of the control circuit H) contains in line 3 a motor-start relay M which when energized closes the contacts M-1, M-2 and M-3 starting the motor. To supply current to the relay M, a bar-run selector switch 28, also in line 3, must be moved to the "run" position, closing the contacts 30, and a motor-start button 32 must be depressed closing the contacts 34 for this button. Also included in the motor-start circuit are overload contacts 36 opened on overload of the motor, and a plurality of switches and contacts to be described.

Between the motor-start button 32 and the motor-start relay M, a lead 38 is connected to the clutch circuit K, which includes lines 7-15 of the control circuit, the clutch circuit being connected so that the lines 7-15 are in parallel with the motor-start relay M. Included in lead 38 are contacts 40 closed by the bar-run selector switch 28 when the latter is shifted to the "run" position.

The "run" portion L of the clutch circuit includes lines 7-11 connected to the lead 38 through the part of line 7 which contains normally open contacts M-4 closed when the motor-start relay M (line 3) is energized. Also in this part of line 7 are contacts 44 of a jog-run selector switch 46, which are closed when this selector switch is moved to the "run" position.

The "jog" portion N of the clutch circuit includes line 12 connected to the lead 38 through contacts 48 of the jog-run selector switch 46, closed when the selector switch is in the "jog" position.

At this point, it is also worthwhile noting the existence of the run-jog buttons 50 and 52, and the contacts 54, 56 (in line 8); 58, 60 (in line 9); and 62, 64 (in line 12) of these buttons. The contacts of line 8, items 54 and 56, are normally closed, while those of lines 9 and 12 are normally open. Such run-jog buttons are conventional, requiring the operator to use both

hands to engage the clutch, whether the press is being jogged or advanced forwardly in steps, or whether the press is being run through a desired stroke. Regardless of which operation is being performed it is necessary that both of the run-jog buttons be pressed. Also to be noted are coils 66 and 68 (in lines 11 and 12) for the dual clutch valve solenoids. These coils are connected to the "run" portion of the circuit through lines 11 or 9, and to the "jog" portion of the circuit through lines 10 and 11.

10 Line 11 contains a limit switch RLS-1, actuated by cam means 26, and is known as a holding circuit to transmit current to the coils 66 and 68 once the press has started and the run-jog buttons are released opening line 9.

15 The reason for the use of two clutch valves requiring dual coils has already been mentioned, namely if one fails, the other provides a backup. This is also known.

Added to the above circuit in accordance with the present invention, is a line 15 which is connected with lead 38 so that it also is in parallel with the motor solenoid M. This line contains the coil 70 for the solenoid 24 of master solenoid valve E of FIG. 1. Also added is a line 14, connected in parallel with line 15, containing a relay CRX to be described. Further, to be noted, are switches PS-2, LS-A and LS-B (mentioned with reference to FIG. 1) having switch contacts 72 and 74 (for PS-2) in lines 8 and 11, respectively; and contacts 76, 78, 80 and 82 (for LS-A and LS-B) in lines 8, 14 and 14a, respectively. As described with reference to FIG. 1, the pressure switch PS-2 is connected to the outlet port of the master solenoid valve. The contacts 72 in line 8 are normally closed, while those in line 11 (item 74) are normally open; but on opening of the master solenoid valve, the positions of these contacts change, so that those in line 8 are opened and those in line 11 are closed.

35 It was also described with reference to FIG. 1 that the switches LS-A and LS-B were actuated in response to movement of the poppets for the dual clutch valve. Accordingly on opening the valve, the normally closed contacts 76 and 80 in line 8 for these switches are opened and the normally open contacts 82 and 78 in lines 14 and 14a for these switches are closed.

With this broad orientation of the electrical circuit, details of the circuit will now be described, first with respect to "run" operation of the press.

45 In this respect, this is a single-stroke press requiring the operator to restart the press after each stroke, although the principles of the invention are applicable to a continuous stroke or multistroke press, which is operable on a single-stroke basis.

50 With the bar-run contacts in lines 3 and 6 in the closed position, pressing the motor-start button 32 transmits a current to the motor relay M. If the jog-run button in line 7 is in the "run" position, with the contacts in line 7 closed, the current passes through contacts M-4 in line 7; and through the normally closed contacts 54, 56 of the run-jog buttons, the normally closed contacts 72 of pressure switch PS-2, and the normally closed contacts 76 and 80 of switches LS-A and LS-B, all in line 8; to energize relay 1CR.

60 This relay is an antirepeat relay, for single stroke operation of the press. Although its function will be described in detail, it is sufficient to note that it opens normally closed contacts 1CR-1 and 1CR-2 in lines 3 and 4, and closes normally open contacts 1CR-3 in line 9, and 1CR-4 in line 7, those of line 7 being hold contacts for the relay. This means that when the contacts of line 8 are opened, after energizing the line, relay 1CR remains energized through line 7. Also in line 7 is switch RLS-3 actuated by cam means 26 (FIG. 1), relay 1CR remaining energized only so long as this switch remains closed.

65 Line 9, which contains normally open contacts 1CR-3 (closed when relay 1CR is energized) and contacts 58, 60 of the run-jog buttons, leads to two clutch relays 2CR and 3CR, lines 9 and 10. These two relays are identical, and are merely duplicates to reduce the chances of clutch actuation and engagement by virtue of relay malfunction. In this respect, the

relays 2CR and 3CR close normally open contacts 2CR-1, and -2, and 3CR-1 and -2, in lines 10 and 11, for an input current to the terminals of the dual clutch valve coils 66 and 68, through lines 9, 10 and 11. The relays also close contacts 2CR-3 and 3CR-3 in line 15 for an input current to master solenoid valve coil 70. The importance of the relays should be apparent, since it is only by energizing these relays that the clutch is engaged. By having the two relays in parallel, should one of the relays fail in the energized position, the clutch would still not be engaged because of proper operation of the other relay.

Also energized by relays 2CR and 3CR are normally closed contacts 2CR-4 and 3CR-4 in line 8. Although these contacts will be discussed in greater detail, they prevent the antirepeat relay 1CR from being energized should either or both relays 2CR and 3CR fail in the energized position.

The primary function of the antirepeat relay can now be discussed. Should the run-jog buttons 50 and 52 inadvertently remain in the depressed position, relay 1CR would be deenergized on opening switch RLS-3 in the hold circuit (line 7), opening contacts 1CR-3 of line 9. At about 310° of the stroke RLS-1 of line 11 (the holding circuit) opens deenergizing the clutch relays 2CR and 3CR. This prevents a restroke of the press until relay 1CR can be reenergized by closing line 8 through contacts 54 and 56 of the run-jog buttons; *i.e.*, by releasing the buttons from the depressed position. The antirepeat relay in effect prevents a restroke should the operator hold the run-jog buttons in the depressed position, or should they remain depressed for some other reason.

The purpose of normally open contact CRX-1 in the holding circuit, line 11, is to prevent the flow of current to the terminals of the dual valve coils (through the contacts of relays 2CR and 3CR and the normally open switch 74 of PS-2) unless the clutch valves are already in an open position; *i.e.*, unless contacts 78 and 82 (lines 14 and 14A) of the switches LSA and LSB are closed and relay CRX energized. This will be discussed in greater detail.

Also responsive to the relay CRX are normally closed contacts CRX-2 and CRX-3 in lines 3 and 4 respectively.

Requiring mention at this point is switch RLS-4 in line 5 in parallel with the normally closed contact CRX-3. Actuation of the dual clutch valve spools causes the CRX-3 contact to open and the current to flow through RLS-4. Referring to FIG. 2A, it can be seen that this switch is opened at about 340°, at which point the flow of current to relay M is through CRX-3 (closed at about 300° with deenergizing relay CRX on opening the clutch valves). Switch RLS-4 is opened only momentarily for the purpose of checking that the important interlocking relay is operative.

In operation, pressing the motor-start button 32 in line 3 energizes relay M which in turn closes hold contacts M-5 in line 4 to maintain a flow of current to the relay after the motor-start button is released. Also closed are contacts M-4 in line 7 for energizing the clutch circuit K.

Relay 1CR also is energized closing contacts 1CR-3 in line 9 so that on depressing the run-jog buttons 50, 52 relays 2CR and 3CR are energized. This closes the contacts to the dual clutch valve and master solenoid valve coils, energizing these coils, opening the respective valves and causing the clutch to be engaged with the running motor, and the press crankshaft to be turned.

It should be noted at this point, that contacts 1CR-2 and CRX-3 in line 4 are now in the open position actuated by energized relays 1CR and CRX, line 14, the latter with opening of the dual clutch valve. Accordingly the hold current to motor relay M is through switches RLS-2 (closed to about 220°) and RLS-4 (closed to about 340°).

While the run-jog buttons (50, 52) are depressed, the hold current for relay 1CR is through switch RLS-3 (line 7) which is closed at start of the press, and opened at about 200°.

The operator must hold the run-jog buttons depressed for a predetermined part of the stroke, in this case about 160°, until switch RLS-1 in line 11 is closed. After this point the current

flow to the dual clutch valve coils is maintained through the holding circuit of line 11, including the closed (normally open) contacts CRX-1, of this line, and the closed (normally open) contacts 74 of switch PS-2, of the same line.

5 The master solenoid valve coil 70, line 14, remains energized by virtue of the flow of current through the closed (normally open) contacts 2CR-1, -2 and 3CR-1, -2 of lines 10 and 11 to relays 2CR, 3CR, closing the contacts 2CR-3 and 3CR-3 in line 15.

10 Switch RLS-3 of the hold circuit (line 7) for relay 1CR opens at about 200°, and at this point the antirepeat relay 1CR becomes deenergized since the normally closed contacts 2CR-4 and 3CR-4 in line 8 are in an open condition, and remain open until near the end of the press stroke (about 300°) when RLS-1 (line 11) opens deenergizing relays 2CR and 3CR. Contacts 72 of pressure switch PS-2, and 76, 80 of switches LSA, LSB also prevent 1CR from being reenergized.

At this point (about 300°) the master solenoid valve coil and dual clutch valve coils (lines 15, 11 and 12) also become deenergized (as the 2CR and 3CR contacts open) disengaging the press clutch.

Also at this point, contact 1CR-2 in line 4 closes to its normally closed position. Since RLS-2 (line 5) opens shortly after RLS-3 opens, at about 220°, the hold current for relay M from then on is through 1CR-2 and RLS-4 in series. Ultimately, at about 340° RLS-4 opens momentarily.

With deenergizing relays 2CR and 3CR in lines 9 and 10, the dual clutch valve and master solenoid valve close, as well as contacts 2CR-4 and 3CR-4 in line 8. Relay CRX in line 14 is deenergized closing contacts CRX-2, -3, lines 3 and 4 readying the press for restarting. Also to permit restarting, switch RLS-3, line 7, contacts 72, 76, 78, line 8, and switches RLS-2 and RLS-4 have been closed.

35 For jogging the press, the jog-run selector switch 46 is shifted so that the contacts 48 for this switch in line 12 are closed and those of line 7 (44) are open. The press is jogged in its cycle by pressing the run-jog buttons 50, closing the contacts 62, 64, in line 12, permitting the flow of current to the relays 2CR and 3CR and to the input terminals of the dual clutch valve coils 66, 68. This closes the 2CR-3 and 3CR-3 contacts in line 15, permitting the flow of current to the input terminals of the master solenoid valve as well. On release of the run-jog buttons, the current flow is terminated, disengaging the clutch and stopping the press slide.

The safety features of the control are as follows.

If any of the relays, the motor-starter relay M, the antirepeat relay 1CR, the clutch-circuit relays 2CR, 3CR, or the interlocked relay CRX fail in the deenergized position, the press 50 cannot be cycled. The same is true for the solenoids for the dual clutch valve and master solenoid valve.

A critical relay is the antirepeat relay 1CR in line 8 associated with contacts 1CR-3 in line 9 to prevent a repeat stroke in the event the run-jog buttons 52 remain in the depressed position. The relay is deenergized on every stroke by switch RLS-3 opening the contacts 1CR-1. However, if this relay were to fail in the energized position, the press could repeat; *i.e.*, without the important step of depressing the run-jog buttons, since contacts 1CR-3 in line 9 would be closed. This is avoided in accordance with the present invention by providing the normally closed contacts 1CR-1 in motor start line 3 which, would be in an open state preventing motor relay M from being energized (with pressing of the motor-start button). If relay 1CR sticks in the open position after the press motor has started, hold line 4 for relay M also is provided with a normally closed contact 1CR-2 responsive to relay 1CR, and in this case the press motor would stop when switch RLS-2 in parallel with 1CR-2 is opened, at about 210°.

70 Other critical relays are 2CR and 3CR and it has already been mentioned that the use of these two relays in series provides substantial safety with respect to engagement of the clutch, in this case actuation of both the dual clutch valve and master solenoid valve. In this case, and in conventional systems, the relays prevent actuation of the clutch valves

(through the switch RLS-1 should the switch stick in the closed position) prior to depressing the run-jog buttons. However, should both relays fail in the energized position, then the 2CR and 3CR contacts, lines 10, 11, and 15 would be closed and the dual clutch valve coils would be energized. Also the master solenoid valve coil would be energized allowing air to get to the clutch. To prevent this the normally opened contacts CRX-1 of relay CRX are provided in line 11, which would not be closed until the dual clutch valve is first closed (by virtue of contacts 82 and 78, lines 14 and 14A). Also preventing energizing of the dual clutch valve coils, should 10 2CR and 3CR fail in the energized position, are normally closed contacts 2CR-4 and 3CR-4 in line 8, preventing the flow of current to relay 1CR, and closing of contacts 1CR-1 in line 9.

Should the relay CRX in line 14 fail in the energized position, an interlock again is provided which includes normally closed contacts CRX-2, -3 in lines 3 and 4, which would open preventing the flow of current in these lines to the motor relay M either at start or during hold. This interlocking is similar to that employed with respect to relay 1CR, except in this case, the motor would stop on opening of switch RLS-4 of line 5 in parallel with the CRX-3 contact in line 4.

The interlocking relay CRX is an important relay. After substantial use, these relays can become sluggish delaying their being deenergized. As an alternative, it may be desirable to connect line 14 to line 3 ahead of the motor-start button to prevent cycling of the press should the relay become sluggish. The relay would thereby remain energized and contacts CRX-2 and CRX-3 would remain open.

Provision also is made in the circuit for: failure of the dual clutch valve F should it be stuck in the open position, whether from residual magnetism or sticking of any combination of internal components in the valve body; and for failure of the master solenoid valve E in the open position. With respect to the former, opening of the dual clutch valve closes the contacts 78 and 82 in line 14, energizing relay CRX, opening the normally closed CRX-2, -3 contacts in lines 3 and 4. This prevents the flow of current to the motor relay on pressing the motor-start button, or during hold. In this respect, if the dual clutch valve were to become stuck while the press was stroking, the CRX-3 contact in line 4 would remain open, and when limit switch RLS-4 (line 5) opens, the motor would be stopped. In addition, the contacts 76 and 80 in line 8 would be open, preventing the clutch relays 2CR and 3CR from being energized. This would prevent the press from being stroked, as the master solenoid valve could not be energized, contacts 2CR-3 and 3CR-3 in line 15 being in the open position.

With respect to the master solenoid valve, should this valve fail in the open position, the switch PS-2 contacts 72, in line 8, would open opening the run-jog circuit preventing the clutch from being engaged.

It should be apparent that the present invention affords novel and improved circuit and interlock arrangement by which a single stroke press can be effectively prevented from starting in the event of a malfunction, or from inadvertent repeat cycles.

Although the principles of the present invention have been described with respect to a single stroke press, it should be apparent to those skilled in the art that they can be equally as well applied to a press which is adapted for continuous stroking, as well as single stroking and jogging.

Also, although the invention has been described with reference to specific embodiments, variations within the scope of the following claims will be apparent to those skilled in the art.

I claim:

1. A machine control comprising:
a clutch mechanism C and pneumatic circuit FIG. 1 for actuating the clutch mechanism; including a clutch valve F, and a master solenoid valve E in series therewith;
an electrical run circuit FIG. 2 which actuates the clutch valve F and master solenoid valve E; including; a motor relay circuit 15; all in parallel;

clutch relay means 2CR, 3CR including normally open contacts 2CR-1 2, 3, and 3CR-1, 2, 3, in said clutch valve 7-11 and master solenoid valve circuits 15;

dual pushbutton means (50) to energize said clutch relay means 2CR 3CR; a holding circuit 11 in parallel with said dual pushbutton means;

an antirepeat relay circuit 8 and antirepeat relay means 1CR including normally open contacts 1CR-3 in series with said clutch relay means; and said control further comprising interlocking switch means 72, 74, 76, 80 in said holding circuit 11 and antirepeat relay circuit 8 responsive to the positions of said clutch and master solenoid valves.

2. A control according to claim 1 further comprising: interlocking relay means CRX including an interlocking relay circuit 14;

normally closed series disposed contacts CRX-2, 3 and 1CR-1, 2 in series with said motor relay circuit OL, OL,

M responsive to said interlocking relay means CRX and said antirepeat relay means 1CR; holding switch means RLS-2 and 4 in parallel with said series disposed contacts operative to energize said motor relay circuit OL OL, M for a predetermined part of the machine stroke; and said interlocking relay circuit including switch means 78, 82 responsive to the position of said clutch valve F.

3. A control according to claim 2 further including normally open contacts CRX-1 in said holding circuit, in parallel with the dual pushbutton means, responsive to said interlocking relay means CRX.

4. A control system for a press having fluid actuated clutch means C driven by motor means B comprising: electrical motor control circuit means J for energizing said motor means B, a pneumatic circuit FIG. 1 including electrically operated pneumatic valve means F for actuating said clutch means C, an electrical run circuit FIG. 2 for operating said valves means F, said run circuit FIG. 2 including relay means CRX having motor control circuit contacts CRX-2 and CRX-3 in said motor control circuit J, said run circuit including valve operated contact means 78 or 82 operated by said valve means F for operating said relay means CRX said opening of valve means F maintaining said valve operated contact means 78 or 82 in a condition for preventing closing of said motor circuit contacts CRX-2 and CRX-3 by operation of said relay means CRX, whereby sticking of said valve means in an open position prevents driving of said clutch means C by said motor means B.

5. The control system of claim 4 wherein said run circuit includes antirepeat relay means 1CR, and second valve operated contact means 76 or 80 connected in series with said antirepeat relay means for preventing operation of said antirepeat relay means through said second valve operated contact means when said valve means is in an open position.

6. A control system for a press having fluid actuated clutch means C driven by motor means B comprising: electrical motor control circuit means J for energizing said motor means B, a pneumatic circuit FIG. 1 including master valve means E connected in series with dual valve means F for actuating said clutch means C, an electrical run circuit FIG. 2 for operating said valve means E and F, said run circuit FIG. 2 including a pair of relays 1CR and CRX having motor control circuit contacts 1CR-1, 1CR-2, CRX-2, CRX-3 in said motor control circuit J, said run circuit including valve operated contact means 72, 76, 80, 78, 82 operated by said valve means E and F and connected in series with said relay means 1CR and CRX, sticking of either of said relay means 1CR or CRX in an energized condition maintaining at least certain of said motor-control circuit contacts 1CR-1 and 1CR-2 or CRX-2 and CRX-3 in an open position to prevent energization of said motor through said run circuit for repeat cycles of said press, failure of either of said valve means E or F in an open position maintaining at least certain of said valve operated contacts 72 or 76 or 80 in an open position to prevent energization of at least

one of said relays 1CR for repeat cycles of said press, and failure of at least one of said valve means F in an open position maintaining at least certain of said valve operated contacts 78 or 82 in a closed position to maintain the other of said relays CRX energized and hold at least certain of said motor-control circuit contacts CRX-2 and CRX-3 in an open position for preventing energization of said motor means (B) in repeat cycles of said press.

7. A press control system comprising:

a clutch mechanism C; 10
 a pneumatic means for actuating said clutch mechanism C;
 air supply means D;
 a dual clutch solenoid valve between said air supply means and said pneumatic means F;
 an electrical run circuit for said press comprising FIG. 2; 15
 a motor relay circuit OL OL, M and a dual clutch valve solenoid circuit 7—11 in parallel;
 a first normally closed contact means in series with said circuits 1CR-1, 1CR-2;
 said clutch circuit including first 9 and second 11 parallel 20 lines connected to the dual clutch valve solenoids, 66 and 68 the first line containing dual pushbutton contacts 58 and 60 in series;
 the second line containing a normally open holding switch RLS-1 to energize the clutch valve solenoids 66 and 68 25 when the pushbuttons are released;
 an antirepeat relay means 1CR;
 normally open contacts 1CR-3 responsive to the antirepeat

relay means 1CR in series with said clutch valve solenoid, 66 and 68 said first normally closed contact 1CR-1, 1CR-2 means being responsive to the antirepeat relay 1CR; the improvement comprising:
 a master solenoid valve E between said air supply means D and said dual clutch solenoid valve F;
 air pressure switch means PS-2 responsive to the pressure on the output side of said master solenoid valve E;
 a master solenoid valve circuit in parallel with said first and second parallel circuits;
 a second normally closed contact means CRX-2 CRX-3 in series with said circuits;
 interlocking relay means CRX including normally open contacts CRX-1 in series with said holding switch RLS-1; the second of said normally closed contacts CRX-1 being responsive to said interlocking relay means CRX;
 normally open switch means 78 and 82 in series with said interlocking relay means CRX closed when said clutch valve F is energized to the open position;
 normally closed switch means 72, 76, 80 in series with said antirepeat relay means 1(CR) opened when said clutch valve F or master solenoid valve E;
 either or both, are actuated to the open position; and
 normally open switch means 74 also in series with said holding switch closed when said master solenoid valve 70 and E is actuated to the open position.
